UNITED STATES PATENT OFFICE.

GARY B. SMITH, OF CHICAGO, ILLINOIS.

CROSS-TIE CHAIN FABRIC FOR BED-SPRINGS.

1,247,024.

Specification of Letters Patent. Patented Nov. 20, 1917.

Application filed February 20, 1917. Serial No. 149,941.

To all whom it may concern:

Be it known that I, GARY B. SMITH, a citizen of the United States, residing at Chicago, in the county of Cook and State 5 of Illinois, have invented a new and useful Cross-Tie Chain Fabric for Bed-Springs, of which the following is a specification.

The present invention appertains generally to bed spring fabrics, and is particularly an improvement over the interlocking hook for wire fabric disclosed in my Patent 10 No. 933,130 granted September 7, 1909.

It has been found that the fabric disclosed in said patent possesses certain disadvantages, in that first, the cross ties cannot be made in continuous chains, since the cross ties or links are not interlocked; second, the fabric becomes tangled when handled free from the frame or supporting means; and 20 third, the liability of the cross ties or links giving way when subjected to excessive or abnormal strains. These are the main objections to the fabric disclosed in said patent, but there are other incidental ones.

25 It is the object of this invention to provide novel means for assembling the cross ties or links with one another and with the strands, whereby the above-mentioned and other objections are overcome. Thus, the 30 cross ties or links can be made in continuous chains which can be wound upon spools, for the purpose of assembling the ties or links easily and quickly with the strand or strands.

35 The present construction also eliminates the tangling of the fabric when handled free of the frame or supporting means, in shipping, etc. The cross ties or links are also telescopically or slidably connected 40 with each other, and are prevented from sliding into engagement with any of the strands except those with which the ties or links are assembled, thus avoiding tangling, and furthermore, this provides for 45 the effective depression of the strands at any point of the fabric without pulling or displacing the strands at other portions of the fabric, in order that persons of different weights can rest comfortably upon the fabric. 50 This action of the fabric is enhanced by reason of the fact that the cross ties or links are longer than the spaces between the strands. The cross ties or links are so constructed that they interlock and are prevented from unbending or being disengaged 55

from the strands by the excessive separation of the strands or the excessive or abnormal strains on the cross chains. In fact, the excessive tensile strain on the chains will even more tightly clench or lock the cross ties or links on the strands, thus enabling the chains to extend longitudinally of the fabric if desired, since they can resist the tensile strains with thorough effectiveness. Furthermore, wire of smaller gage can be 60 used for the cross ties or links, and the length of stock used for the cross ties or links is also decreased, thereby effecting a saving in material. The present invention therefore provides for economy, both in 65 the material used, and the work in assembling the fabric, and the fabric is superior to that employed in said patent.

With the foregoing and other objects in view which will appear as the description 75 proceeds, the invention resides in the combination and arrangement of parts and in the details of construction hereinafter described and claimed, it being understood that changes in the precise embodiment of 80 the invention herein disclosed can be made within the scope of what is claimed, without departing from the spirit of the invention.

The invention is illustrated in the accompanying drawings, wherein—

85 Fig. 1 is a plan view of the improved fabric, portions being broken away.

Fig. 2 is a section on the line 2—2 of Fig. 1.

Fig. 3 is a fragmental perspective view 90 of one of the chains as it comes from the machine which makes it, and as it is wound on the spool before assemblage with the strands.

Fig. 4 is sectional detail illustrating how 95 the cross ties or links of each pair interlock when there is a pull in opposite directions upon them.

Fig. 5 is a view similar to Fig. 1 illustrating a modification.

100 The fabric embodies substantially parallel strands 1 disposed side by side and extending longitudinally, as seen in Fig. 1, and their ends are connected by means of coiled wire springs 2 or otherwise with the frame 105 or supporting means. As illustrated, the strands 1 are composed of one piece of cable or twisted wire extending back and forth from one end to the other, although the strands may be of any suitable formation.

110

110

The invention resides in the construction of the cross chains and the manner of assembling the links thereof with each other and with the strands. There are a plurality 5 of these cross chains spaced longitudinally and extending transversely across the strands. Each chain comprises a series of cross ties or links 3, each formed of a length of wire doubled upon itself to provide the members 4 diverging away from one another from the ends of the wire, and connected at their ends which are spaced farthest apart by a U-shaped loop 5. This loop 5 is bent at an obtuse angle from the plane 10 of the members 4 or the plane of the body of the link, the loop being located at one end of the link and constituting the intermediate portion of the wire, while the ends of the wire are bent back toward the same side to 15 ward which the loop 5 is bent, thereby providing the hook 6 at the other end of the link and from which the members 4 diverge. When the chain is manufactured and wound upon the spool, preparatory to assemblage 20 with the strands 1, the loops 5 are seated in the hooks 6, as seen in Fig. 3, thereby providing a continuous chain which can be readily manufactured, spooled and assembled with the strands, instead of merely handling the cross ties or links individually. It 25 will be noted that the loops 5 are not bent back into hook form, as in said patent, thereby providing a saving in material.

When the chains are assembled with the 30 strands, each cross tie or link 3 extends across and rests upon two adjacent strands, and the hook 6 of each link engages under and is clenched tightly into engagement with the respective strand, so that the hook projects 35 upwardly in an inclined direction or at any acute angle toward the members 4, the link therefore being held in place relative to the strand to which it is clenched. Each link is thus clenched to one strand and the members 4 thereof rest slidably upon the companion or adjacent strand at opposite sides of the respective end of the companion link and its hook 6, with the loop 5 extending loosely under and slidably engaging said 40 companion link beyond its hook 6, as seen in Fig. 2. Each link is longer than the space between the respective strands, whereby its loop 5 slides under the companion link to and from its hook 6, which enables 45 the strands to move toward and away from one another to a limited amount. This permits the fabric to be depressed at various points in an effective manner. Supposing that one or more strands are depressed at 50 one point of the fabric, these strands can separate, since the links can separate a certain amount due to their sliding or telescopic connection, without pulling the strands at other portions of the fabric out of place, unless the depression of the fabric 55

is excessive or abnormal. The links thus rest slidably upon the strands at the free or looped ends of the links, the other ends of the links being clenched to the respective strands, and the free ends of the links have 60 the loops engaging slidably under the companion links, whereby the links are interlocked. It will be noted, however, that the loop 5' at one end of each chain is bent back into a hook to embrace the respective strand 65 1, in order to attach the corresponding end of the chain or anchor it to the side strand.

By reason of the present assemblage of the links with each other and with the strands, it will be observed that when there 70 is an excessive separation of the strands and links, so as to produce an excessive or abnormal tensile strain on the cross chain, the loops 5 will be slid under and in engagement with the clenched hooks 6, as seen in 75 Fig. 4, and said loops also bear against the respective strands 1, whereby when the links of each pair separate, as seen in Fig. 4, the looped end of one link will resist the unbending of the corresponding hook 6. This 80 is due to the fact that the loop 5 will engage the hook 6 with a cam action, and clamp or hold said hook 6 in closed position, and in fact, the greater the strain is, the tighter will the hook 6 be held closed, thus 85 90 successfully resisting the unbending of the hook or the excessive separation of the strands and links. Thus, although when the loops 5 slidably engage the companion links, and move away from the hooks 6 when the strands are in normal position, yet when the strands and links are separated a certain amount, the loops will move in engagement with the hooks and strands to hold the parts 95 assembled and to resist the tearing apart of 100 the strands and cross ties or links. It will also be noted that in handling the fabric 105 free from its frame or supporting means, each link 3 can only slide a certain amount on its companion link, since when the loop 110 of one link moves a certain distance toward the loop 5 of the companion link, the movement of the two links toward one another is stopped, due to the angular position of the members 4, each link increasing in width 115 from its hooked end to its looped end. Consequently, when two links are moved toward one another in telescopic relation, the members 4 of one link will wedge within the loop 5 and members 4 of the other member 120 thereby limiting their movement, and this eliminates the tangling of the fabric. Tangling is also avoided due to the fact that the loops 5 are not bent into hook form, as in 125 the fabric disclosed in said patent.

As above indicated, the chains can be disposed longitudinally, and this is illustrated in Fig. 5, wherein the chains are connected at their ends with the springs 2, while the strands 1 are disposed transversely. The in- 130

terlocking feature of the links enables the chains to withstand the strains to which they are subjected.

From the foregoing, taken in connection with the drawings, the advantages and attributes of the present invention will no doubt be apparent, without further comment being necessary.

Having thus described the invention, what is claimed is:—

1. A fabric embodying strands and cross chains extending across the strands and each embodying slidably connected links, each link being composed of doubled wire throughout its length having its ends bent into a hook embracing one strand and inclined, the link having a loop at that end opposite to the hook slidably engaging the companion link and movable into engagement by a cam action with the hook of the companion link.

2. A fabric embodying strands and cross-tie links resting upon the strands, each link composed of doubled wire throughout its length having an inclined hook at one end 25 engaging under and clenched to one strand, each link having members diverging from the hook and a loop connecting those ends of the members spaced farthest apart, said loop extending downwardly at an obtuse 30 angle and sliding under the members of the companion link, the loops being movable into engagement by cam action with the hooks of the companion links to prevent the unbending thereof. 35

In testimony that I claim the foregoing as my own, I have hereto affixed my signature in the presence of two witnesses.

GARY B. SMITH.
